UNITED STATES PATENT OFFICE.

GEORGE P. WIEGNER, OF DONNELLSON, IOWA.

RADIOTUBE.

Application filed January 19, 1925. Serial No. 3,445.

This invention relates to radio apparatus, particularly to thermionic triodes, or vacuum tubes, and has for its object the provision of a novel tube embodying various characteristics of construction and arrangement whereby to be extremely sensitive and more efficient than the ordinary type in common use.

A very important object is the provision of a vacuum tube which may be used either for radio frequency amplification, audio frequency amplification or detection with equal facility and efficiency and which is moreover so constructed and arranged as to reduce the internal capacity to the minimum.

Another important feature is the provision of a vacuum tube having a peculiar construction and arrangement of plate, grid and filament whereby to obtain many advantages such, for instance, as smoothness of operation, clearness of result, freedom from tube noises, and the like.

A further object is the provision of a vacuum tube in which the filament consists of a plurality of lengths arranged at equal distances apart and in parallel relation not only to one another but to the grid and also to the plate element.

Still another object is the provision of a vacuum tube in which all portions of the filament, or lengths thereof, are equally spaced from the grid, and in which all portions of the grid are equally spaced from the plate element.

Another important object is the provision of a vacuum tube in which means is provided for constantly applying tension to the filament and consequently preventing it from sagging at any time and varying its distance from the grid or even possibly permitting it to come into contact with the grid when the filament expands under the influence of heat.

A specific object is the provision of a vacuum tube in which the filament is firmly anchored at one end but connected at its other end with a member of a supporting nature movable longitudinally of the tube or the support within the tube and equipped with spring means tending to effect movement in one direction so as to hold the filament taut and prevent sagging thereof under any conditions.

An additional object is the provision of a device of this character in which the terminal elements are brought out through the

sides of the tube face for cooperation with contact elements of a socket, the location of the terminals at the side being of advantage in reducing the capacity and increasing the efficiency of the tube.

The invention further contemplates the provision of various details of construction which will constitute a material improvement in the art in point of ease of assembling, strength and durability in service, and other meritorious features.

With the above and other objects and advantages in view, the invention consists in the details of construction to be hereinafter more fully described and claimed and illustrated in the accompanying drawings, in which:

Figure 1 is a longitudinal section through a vacuum tube constructed in accordance with my invention,

Figure 2 is a vertical section on the line 2—2 of Figure 1 with certain parts shown in elevation,

Figure 3 is an end elevation of the base, 80

Figure 4 is a side elevation of the internal support, portions thereof being broken away and in section,

Figure 5 is a detail perspective view of the grid element, 85

Figure 6 is a section on the line 6—6 of Figure 4,

Figure 7 is a fragmentary perspective view of the lower portion of the plate element, 90

Figure 8 is a plan view of a suitable socket in connection with which the tube may be used.

Referring more particularly to the drawings, I have shown a vacuum tube including a base 10 of shell like formation to which is secured, in any desired manner, the bulb 11 which is ordinarily of glass and which may be of any desired size and shape. Carried by the shell or base and located within the bulb is the support designated broadly by the numeral 12, which support includes a bottom portion 13 of circular formation, from which rises a flat or relatively wide and thin shank 14 carrying an upstanding elongated loop like frame 15 at the top of which is a cross member 16. In actual practice all the parts are preferably formed integrally from some such material as glass or the like.

Located within the upstanding frame 15 is the plate element designated broadly by the numeral 17, which plate element is prefer-

- ably formed of upper and lower members 18 of similar construction between which extend and to which are secured strips, sheets or ribbons 19 of suitable wire mesh.
- 5 Each of the members 18 is shown as being of substantially U-shape including a bridge portion 20 and relatively long arms 21, to the edges of the latter of which are welded or otherwise fastened the ends of the wire 10 strips or ribbons 19. The plate element is mounted in place in such manner that the upper and lower metallic members 18 fit within and against the upper and lower inner portions of the upright frame 15 as 15 clearly disclosed. Securing may be effected in any desired manner so I have illustrated screws or rivets 22 which pass through holes 23 in the arm 21 and through the sides of the frame 15.
- 20 A conductor or lead 24 is connected with one of the screws or rivets 22 and is brought down along one side of the frame 15, through the bottom portion 13 of the support 12 and along within the shell 10 of 25 the base. Extending through the shell or base is a terminal pin 25 with which this lead or conductor 24 is connected.
- Located within or between the opposite sides of the plate element 17 is the grid 30 designated broadly by the numeral 26; which grid is shown as constructed of two similar sections 27 each formed as a substantially U-shaped wire frame having its sides connected by a plurality of transverse wires 35 28. The upper ends of the sides of the frames 27 preferably converge slightly as shown, and have their terminals inwardly directed, or extended toward each other as shown at 29. The cross member 16 is 40 formed with holes 30 through which the terminals 29 are engaged whereby to suspend the grid properly within the confines of the plate element. The bight portions of the two frames 27 forming the grid are 45 brought together and secured by any desired means as shown at 31, and connected at this point is a conductor or lead 32 which is brought downwardly in a diagonal direction so as to avoid the bridge portion 20 50 of the lower metallic member 18 of the plate structure. This lead 32 passes through the bottom portion 13 of the support 12 and along the inner periphery of the shell or base 10 where it connects with a pin 33 projecting laterally through the shell 10 diametrically opposite the above described pin 25. The purpose of this exact arrangement of the leads is to keep them separated as far as possible and prevent capacity 55 effect.
- The filament of the tube is designated broadly by the numeral 34 and includes a plurality of strands or lengths 35 arranged at equal distances apart. For supporting 60 the filament I provide pins or posts 36 of angular formation embedded or otherwise secured in the shank portion 14 of the support 12 and having terminal eyes 37 through which the filament is threaded. The outer ends of the filament are connected with 70 leads or conductors 38 which extend through portions of the shank 14 of the support 12 and through the bottom portion 13 of the support 12 and downwardly along the inner periphery of the shell 10 where they 75 connect with pins 39 similar to the pins 25 and 33 and arranged in the same manner.
- For supporting the upper end of the entire filament I provide a transverse element 40 carrying eyed suspension elements 41 80 through which the filament is threaded as clearly indicated in Figure 4. For maintaining tension upon the filament at all times use is made of serpentine springs 42 which are of U-shape and which have their 85 bight portion passing through suitable holes 43 in the cross piece 16 with their ends connected with the transverse element 40 in any desired manner. Obviously these springs 42 will apply an upward tension on the transverse element 40 at all times so that the filament will be kept taut and be prevented from sagging when in expanded position under the influence of heat.
- Attention is invited to the fact that the 90 terminal pins 25, 33 and 39 all extend laterally from the shell of the base 10, a circumstance which makes it necessary to employ either a special socket or a modified socket 95 for mounting the tube. In the present instance I have illustrated a socket including a base portion 44 and an upstanding shell portion 45, the base carrying the usual binding posts 46 with which are connected 100 spring contacts 47 for cooperation and engagement with the terminal pins on the base of the tube. However, the ordinary type of tube has these terminal pins projecting from the bottom or parallel with the longitudinal axis whereas in the present instance the pins extend longitudinally with respect to the axis of the tube. As a consequence it is necessary that the spring contacts 47 be of angular formation or be 105 extended upwardly as indicated in Figure 1 so as to engage against the terminal pins of the tube. In case a specially constructed socket is employed these springs would of course be made this way in the first place but if an ordinary socket is to be modified it is merely necessary that the spring contact thereof be bent upwardly into the shape shown whereupon an ordinary socket 110 may be used just as well as a specially 115 constructed one.
- In order that the tube may be used in an ordinary socket I have shown the shell 10 as pressed inwardly at spaced points as indicated at 48 with the terminal pins projecting within these depressed portions.

The purpose of these depressions is to accommodate the upstanding portions of the contact springs 47 of the socket. Furthermore, attention is invited to the fact that 5 the terminals or ends of the contact are bent inwardly and then outwardly as indicated at 49 so that they will act to prevent the tube from moving upwardly out of the socket when it is in applied position.

10 In actual practice, the tube is used in exactly the same manner as any other vacuum tube having three electrodes, there being no difference whatsoever in the mode of connecting. However, I have observed that 15 the disposition of the pins in the base projecting from the sides thereof instead of the bottom is of material advantage inasmuch as these pins are kept widely separated as are also the leads which extend to the filament, the grid and the plate, all of these 20 features combining to reduce the internal capacity of the tube and consequently increase the efficiency. Attention is further invited to the fact that the grid is at the 25 same distance from the plate at all points and the filament is likewise equally spaced from the grid at all points. Another distinct feature of advantage is that the various lengths of the filament are of equal 30 distances apart and are parallel. The employment of the spring device for holding the filament taut when in expanded position is of prime importance inasmuch as it prevents the filament from sagging when in a 35 heated condition. Under ordinary circumstances or in ordinary tube it is well known that the filament frequently sags especially

after prolonged use and there is then danger of its contacting with the grid. A feature of advantage in the employment of a 40 plate element formed as a wire screen is that all surfaces are utilized whereas in the case of a solid sheet plate there is only one surface which is active.

From the foregoing description and a 45 study of the drawings it will be apparent that I have thus provided a simply constructed and highly efficient vacuum tube which is well adapted for use in all phases of radio communication and which possesses 50 so many meritorious features as to readily recommend itself to those skilled in the art.

While I have shown and described the preferred embodiment of the invention, it should be understood that I reserve the 55 right to make such changes in the form, construction and arrangement of parts as will not depart from the spirit of the invention or the scope of the subjoined claim.

Having thus described the invention, I 60 claim:

In a vacuum tube, a base, a bulb carried thereby, a support carried by the base within the bulb and including an upstanding frame member, a plate element located within 65 in the confines of the frame member and including upper and lower metallic U-shaped members located within and conforming to the inner surface of the upper and lower portions of the frame, the plate 70 further including elongated strips of wire mesh secured to said metallic members.

In testimony whereof I affix my signature,
GEORGE P. WIEGNER.
